UNITED STATES PATENT OFFICE.

LEON RAPHAEL LECELLIER, OF VILLEDIEU, FRANCE.

LATCH.

SPECIFICATION forming part of Letters Patent No. 448,298, dated March 17, 1891.

Application filed December 3, 1890. Serial No. 373,414. (No model.)

To all whom it may concern:

Be it known that I, LEON RAPHAEL LECELLIER, of the city of Villedieu, Manche, France, have invented Improvements in Locks, of which the following is a full, clear, and exact description.

My invention relates to improvements in locks on the push-and-pull system, and is illustrated in the accompanying drawings, forming part of this specification, wherein—

Figure 1 represents an inside face view of the lock; Fig. 2, a horizontal section of the same in the locked position; and Fig. 3, a similar section in the unlocked position, the rotary latch being just about to be shot into the catch-box. Fig. 4 is an inside face view of the lock provided with tumbler-levers, and Figs. 5 and 6 are horizontal sections of the same lock with the rotary latch shot and in the unlocked and locked positions, respectively.

Figs. 1, 2, and 3 show the simplest form of rim-lock, *a* being the lock-case, within the rim *b* of which is pivoted on a vertical axis *c* a springless rotary latch *d* of the form shown, which works in combination with a lever *e*, which acts as a pawl or stop by engaging with a shoulder on the latch, and is operated by the pull-and-push handles *f f'*, as hereinafter described. The lock also has a safety-bolt *g*, (which may or may not be acted on by a friction-spring *h*.) operated either from the outside of the door by means of the key or from within the apartment by means of the knobs *i*. For the purpose of locking latch *d* in its shot or projected position this latch *d* is provided with a lug *v*. The bolt *g* has in its side a recess *x*, which allows the passage of the lug *v* by the bolt when said bolt is in its normal position. This bolt is so mounted in the case *a* that by pressing either knob *i* when the lug *v* is not within the recess *x* the said recess will be pushed out of the path of the lug *v*, and the solid portion of the bolt will block the passage of the lug, thereby preventing the latch from being rotated, thereby securely locking the latch.

The inside cover-plate *j* is fixed to the lock-case in the ordinary manner and carries the key-hole and spindle-hole liners *k k*.

The catch-box *l* is beveled at *m*, and the

latch is provided with a lug *o*, adapted to strike against said beveled part *m* in order to cause the latch to make a quarter of a revolution upon its pivot *c* for the purpose of throwing the nose *d* of the latch into the box *l*, the completion of this motion of the latch being insured by a spring *n* within the box *l* bearing against the rounded face *p* of the latch, even though there may be considerable play between the door and its frame.

The action of bevel *m* on lug *o* and of spring *n* on the rounded face *p* will be readily understood by comparing Figs. 3 and 2. In the closed position shown in Fig. 2 the end *g* of the lever *e* is caused by the spring *r* to fall behind the shoulder *s* on the latch *d*, so as to lock it in engagement with the box *l*. The latch is disengaged and the door opened from the inside by pulling the knob *f* (which slides on a fixed pin *t*) and causing the sliding spindle *u* to which it is attached to oscillate latch-lever *e* and disengage it from the shoulders of the latch *d*. The latch is then free to be turned back within the lock-case, as in Fig. 3, which position it is caused to assume by the pressure of the flat side of the nose of the latch against the box *l* in the act of opening the door, the backward motion being limited by lever *e*, as shown in Fig. 3. Similarly the door is opened from the outside by pressing on the knob *f'* on the end of spindle *u*. To lock the latch the latter is provided with a lug *v*, and a bolt *g* is mounted in the lock-casing, said bolt having notches *x x'*, one *x'* to engage the bit of a key, which throws the bolt either up or down, so that the recess *x* will be shifted either in or out of the path of the lug *v*. When the notch *x'* corresponds in position to lug *v*, the latch cannot be retracted even should the latch-lever *e* have been disengaged from shoulder *s*.

The locking-bolt *g* is operated from the outside by a key and from the inside of the apartment directly by the knobs *i*. The lock represented in Figs. 4, 5, and 6 is similar, except that there is no outside knob, and that the locking-bolt *g* is operated from the inside only, so that when it is thus locked the latch cannot be opened from the outside even with a key. To fasten the latch from outside with the key, the tumbler-levers *y* are lifted and a

sliding bolt z is thrown by the key into engagement with a shoulder on the catch d , so as to prevent it turning. In order to unlock from outside, the key is introduced and turned so that it first actuates the bolt z , and then pulled so as to move lever e and disengage the shoulder s . By the rotation of the key the tumbler-levers y are lifted and the sliding bolt z is retracted, and then by pulling on the key while its bit is engaged in the **U**-shaped notch of lever e said lever is moved, so that the latch is completely disengaged.

It is to be remarked, in conclusion, that a very slight movement of the parts is required for locking and unlocking the latch.

The details of construction may be varied without departing from the principle of the invention.

I claim—

- 20 1. In a pull-and-push latch-lock, the combination, with a rotary latch, of a lever engaging with the latch, as described, and operated by the pull-and-push spindle, and of a transversely-sliding bolt operated from the inside by hand and from the outside by a key

for locking the rotary latch in its shot or projected position, as specified.

2. In a pull-and-push latch-lock, the combination, with a rotary latch having two shoulders or recesses, of a lever e , engaging with the latch, as described, and with the pull-and-push spindle, and of a longitudinally-sliding bolt z , engaging in a recess in the latch and adapted to be operated by a key which is controlled by tumbler-levers, as described.

3. In a pull-and-push latch-lock, the combination, with the rotary latch having the lug o and rounded face p , of the striking-bevel m on the catch-box and the spring n within the catch-box for throwing the latch into the locked position, substantially as described.

The foregoing specification of my improvements in locks signed by me this 15th day of November, 1890.

LEON RAPHAEL LECELLIER.
